UNITED STATES PATENT OFFICE.

GEORGE J. DEGENHART, OF SPRINGFIELD, OHIO.

DRAINAGE-TUBE.

1,391,464.

Specification of Letters Patent. Patented Sept. 20, 1921.

Application filed November 8, 1920. Serial No. 422,564.

To all whom it may concern:

Be it known that I, GEORGE J. DEGENHART, a citizen of the United States, residing at Springfield, in the county of Clark and State 5 of Ohio, have invented certain new and useful Improvements in Drainage-Tubes; and I do declare the following to be a full, clear, and exact description of the invention, such as will enable others skilled in the art to 10 which it appertains to make and use the same.

My invention relates to improvements in embalming instruments and more particularly to the drainage tubes used for emptying blood vessels.

One object of the invention is to provide an improved form of drainage tube having a novel slide valve for closing the discharge neck whenever necessary, and in this connection a further object is to make unique provision for limiting the movement of the valve when it is either closed or opened.

Another object of the invention is to form the portion of the tube which penetrates the blood vessel, of a separate piece from the remainder of the device, and to employ a screw-threaded connection between the two, whereby several tube sections of different sizes may be used, as occasion may require.

With the foregoing in view, the invention resides in the novel construction and arrangement of parts hereinafter described and claimed, the descriptive matter being supplemented by the accompanying drawings,

Figure 1 is a side elevation of a drainage tube constructed in accordance with my invention.

Fig. 2 is a longitudinal sectional view showing the valve open.

Fig. 3 is a detail sectional view showing the valve in closed position.

Fig. 4 is a longitudinal section of a smaller tube section which may be used in lieu of that shown in Figs. 1 and 2.

In the drawings above briefly described, the numeral 1 designates an outer tube section or head whose outer end is closed by a screw-plug or the like 2, which plug is here shown as carrying a yoke 3 having a cross bar 4 spaced outwardly from the plug or closure. At a point spaced inwardly from the plug 2, the head 1 is provided with a lateral discharge neck 5 to which a flexible 55 tube is connected in the usual way.

Detachably screw-threaded at 6 to the in-

ner end of the head 1, is an inner relatively long tube section 7 whose free end is by preference cut on an oblique line as at 8, to facilitate insertion into blood vessels. This 60 tube section may be of any adequate size and I intend to equip each one of the devices with several of these tubes of different diameters, any one of which may be applied to the head 1 for use, thereby enabling the 65 embalmer to meet any conditions which may arise.

Slidable within the tube section 7 and adapted to extend beyond the end thereof as shown for instance in Figs. 1 and 2, is a 70 resilient vessel extender 9 which is by preference formed of several wire loops as shown. This vessel extender is carried by and operated by a rod 10 within the device, said rod passing through the plug 2 and the 75 cross bar 4 and having a knob 11 on its outer end. By operating this knob, the extender 9 may be projected, retracted, or rotated, and thus blood clots and the like may be readily broken up, but if any fibrous material in the 80 blood clogs the device, it may be necessary to remove the extender 9 for cleaning. This may be easily done, by unscrewing the plug 2.

For cutting off the discharge of fluid 85 through the neck 5, whenever necessary, a sliding valve 12 is mounted in the tube section 1 to move across the open inner end of said neck, and when closed said valve preferably abuts an annular seat 13 within the 90 tube section 1. When opened, however the valve 12 is positioned beyond the neck 5 and abuts the inner end of the plug 2 as shown in Fig. 2. For operating the valve, I have provided a stem 14 which extends through the 95 plug 2 and in the present showing, this stem is of tubular form to surround the rod 10. An operating knob 15 is provided on the outer end of the stem 14 and this knob is positioned within the yoke 3 so that its outer 100 and inner movements will be limited thereby, thus controlling the movement of the valve 12.

In operation, the proper tube section 7 is attached to the head 1, the usual flexible 105 tube is connected with the outlet neck 5, and the device is then inserted into the vessel to be drained. This having been done, the valve 12 is opened, and the contents of the vessel drained off, any blood clots or the 110 like being effectively broken up by moving the vessel extender 9 longitudinally within

the tube section or by rotating the same. When this extender is in the position shown in Figs. 1 and 2, it prevents the blood vessel from closing in and choking the inlet end 5 of the device. If however said extender is clogged by fibrous matter, it may be withdrawn into the tube section 7, thereby allowing the vessel to collapse and choke the end of said tube section. It is then safe to 10 unscrew the plug 2 and remove the extender and its operating rod for cleaning. This may be done quickly and easily and when the cleaned parts are again inserted, the use of the device may be continued. Whenever 15 desired, the flow or discharge through the neck 5 may be cut off by sliding the valve 12 inwardly to the position shown in Fig. 3.

From the foregoing, taken in connection 20 with the accompanying drawings, it will be seen that although my invention is of comparatively simple and inexpensive nature, it will be highly efficient and desirable in numerous ways. Since probably the best results 25 may be obtained from the details disclosed, such details may be followed, but within the scope of the invention as claimed, numerous minor changes may well be made.

I claim:

1. A drainage device comprising a tube for 30 insertion in a blood vessel, the outer end of said tube having a closure and a discharge neck spaced inwardly from said closure, a vessel extender slidable in and beyond said tube and having an operating rod extending 35 through said closure, and a valve slidable in said tube around said rod for closing said neck, said valve having an operating stem also passing slidably through said closure.

2. A structure as specified in claim 1, said 40 operating stem being of tubular form and surrounding said operating rod.

3. A drainage device comprising a tube for 45 insertion in a blood vessel, the outer end of said tube having a closure and a discharge neck spaced inwardly from said closure, an open yoke carried by said outer end of the tube, and having a cross bar spaced outwardly from said closure, a vessel 50 extender slidable in and beyond said tube, said vessel extender having an operating rod passing slidably through said closure and

extending across said yoke through said cross bar thereof, a sliding valve in said tube for closing said discharge neck, and an operating stem for said valve extending slidably through the aforesaid closure and having an operating knob movable within said yoke. 55

4. A structure as specified in claim 3, said operating stem being of tubular form 60 and surrounding said operating rod.

5. A drainage device comprising a tubular head having a lateral discharge neck, a tube extending from one end of said head for insertion in a vessel to be drained, a plug 65 threaded in the other end of said head and having a yoke provided with a cross bar spaced outwardly from said plug, a valve slidable in said head for closing said discharge neck, and a stem for operating said 70 valve, said stem extending slidably through said plug and having an operating head movable in said yoke.

6. A drainage device of the class described comprising a tube having near its outer end 75 a lateral discharge neck, said outer end being provided with a closure and having an open yoke equipped with a cross bar spaced outwardly from said closure, a sliding valve in said tube for closing said neck, and an operating 80 stem for said valve having a knob movable in said yoke.

7. A drainage device comprising a tube adapted to be inserted in a blood vessel, the outer end of said tube being provided with a 85 lateral discharge neck, a screw-plug threaded in said outer end of the tube and carrying a yoke equipped with a cross bar spaced outwardly from the plug, a sliding valve in said tube for closing said discharge neck, a tubular operating stem extending outwardly 90 from said valve through said plug and having an operating knob movable in said yoke, a vessel extender slidable in the aforesaid tube, and an operating rod for said vessel extender passing slidably through said valve, 95 said tubular operating stem, and said cross bar of the yoke.

In testimony whereof I have hereunto set my hand.

GEORGE J. DEGENHART.
